UNITED STATES PATENT OFFICE.

JAMES CARL, OF WHEELING, WEST VIRGINIA.

SELF FEEDING AND HEATING GREASE-BOX FOR TIN-MILLS.

1,272,914.

Specification of Letters Patent. Patented July 16, 1918.

Application filed January 24, 1918. Serial No. 213,563.

To all whom it may concern:

Be it known that I, JAMES CARL, a citizen of the United States, residing at Wheeling, in the county of Ohio and State of West Virginia, have invented certain new and useful Improvements in Self Feeding and Heating Grease-Boxes for Tin-Mills; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in self-heating and feeding grease boxes for use in connection with tin mills and consists of a simple and efficient device of this nature having various details of construction, combinations and arrangements of parts which will be hereinafter fully described, shown in the accompanying drawings and then specifically defined in the appended claims.

I illustrate my invention in the accompanying drawings, which with the letters of reference marked thereon, form a part of this specification and in which:

30 Figure 1 is a front view showing the application of my invention to a tin mill.

Fig. 2 is a side view of a grease box.

Fig. 3 is a vertical sectional view through the grease box on line 3—3 of Fig. 2, and

35 Fig. 4 is a horizontal section on line 4—4 of Fig. 1.

Reference now being had to the details of the drawings by letter:

A designates the frame of a tin mill of the usual construction and in connection with which the present invention is adapted to be used, and B is a grease box, there being two of these one upon either side of the standard at each end of the rollers of the mill the bearings of which are to be lubricated by the grease within the box. The grease is reduced to a liquid by being heated by the iron passing between the rolls of the tin mill. Said box which may be of any suitable shape is provided with a hinged lid

C, and D are screws fitted in threaded apertures in the box at points opposite adapted to engage the casing to hold the box in place. The bottom of the box has a laterally extending compartment E from which a pipe F leads to the bearing to be lubricated. A valve or other damper, designated by letter H, is mounted horizontally within said compartment E and is designed to close over the inlet and exit pipe F and is actuated by means of the handle I, which is pivotally mounted in an aperture in the bottom wall of the compartment. The wall of the compartment E has an opening K between the laterally extending flanges L, and O is a slide movable between said flanges and the vertical rods or keepers R passing through the flanges, said opening being provided to clear out any grease which may accumulate within the compartment.

In the drawings I have shown a single box as applied to one side of the mill, but it will be understood that two boxes will be placed one upon each side of the mill similarly constructed.

By the provision of a self-feeding and heating grease box made in accordance with my invention, it will be noted that the bearings may be continuously lubricated automatically, the supply being regulated by the valve over the exit pipe. When desired, the device may be easily and quickly removed and replaced, and by the provision of the slide the compartment may be cleaned of any accumulation of grease.

What I claim to be new is:

1. A self feeding and heating grease box for tin mills, comprising a casing, and means for attaching the same to the frame of the mill, said box having a laterally extending compartment with an exit tube leading therefrom, a valve for controlling the inlet to said tube, said compartment having an opening in the side thereof, and a slide controlling said opening.

2. A self-feeding and heating grease box for tin mills, comprising a casing, and means for attaching the same to the frame of the mill, said box having a laterally extending compartment with an exit tube leading

therefrom, a valve for controlling the inlet to said tube, the side of said compartment having laterally extending flanges parallel to each other and also in the side between 5 the flanges, rods extending through the flanges, and a slide mounted between the flanges and held in place by said rods.

In testimony whereof I hereunto affix my signature in presence of two witnesses.

JAMES CARL.

Witnesses.
